UNITED STATES PATENT OFFICE.

EDWARD CHARLES BAUM AND DE WITT OWEN JONES, OF CHICAGO, ILLINOIS,
ASSIGNORS TO ARMOUR FERTILIZER WORKS, OF CHICAGO, ILLINOIS, A COR-
PORATION OF NEW JERSEY.

PRODUCTION OF ALUMINUM CHLORID.

1,372,332.

Specification of Letters Patent.

Patented Mar. 22, 1921.

No Drawing.

Application filed March 24, 1920. Serial No. 368,372.

To all whom it may concern:

Be it known that we, EDWARD CHARLES BAUM and DE WITT OWEN JONES, both citizens of the United States, residing at Chicago, in the county of Cook and State of Illinois, have invented certain new and useful Improvements in Production of Aluminum Chlorid, of which the following is a specification.

10 Heretofore, it has been proposed, or has been customary on a small scale, to produce aluminum chlorid, which is useful and advantageous in many ways including the "cracking" of heavy oils, the production of 15 organic compounds, and in the manufacture of dye stuffs, etc., by the action of chlorin upon heated aluminum, also by heating a mixture of aluminum oxid and carbon in a current of chlorin, the carbon and chlorin not acting separately but by their 20 mutual action the reaction occurs in consequence of the affinity of carbon for oxygen and of chlorin for aluminum. These are not economical processes; first, because the 25 reaction is not exothermic in the case of using alumina and carbon, and accordingly outside heating is required; second, because the production of the metal aluminum is an electrolytic process; and, third, because the 30 metal fuses into a lump in the case of using metal, hence rendering its surface only available for the reaction. Nor are these processes commercially feasible, since chlorin at the necessary temperature is a disagreeable 35 gas to use and is a violent reagent consuming parts of the apparatus when outside heating has to be resorted to.

The leading object and prime purpose of our invention is the economical production 40 of aluminum chlorid, and we have discovered that it can be made from aluminum nitrid and fulfil such requirement for inexpensiveness in manufacture. The nitrid is employed as a source of aluminum to 45 better advantage than the metal proper, because it can be more cheaply produced without the practice of an electrolytic process, because it does not fuse at the temperature employed, and because the reaction is 50 economically exothermic.

The new process consists in producing the aluminum chlorid from the aluminum nitrid by the direct action of chlorin gas thereon, by the development of heat attending the re-

action being sufficient to continue the chemical transformation after it has once been well inaugurated or established.

In the actual commercial practice of the method, a fire-brick-lined cylindrical shaft or tube of about 12 inches in diameter and approximately 4 feet in height is internally heated in any approved manner, as by the burning of gas, until it becomes quite hot. The aluminum nitrid, in the form of briquets of convenient size, containing about 4 to 5 per cent. of carbon and possibly a small amount of aluminum oxid which has not been converted into aluminum nitrid, such briquets being conveniently used in the form in which they are discharged from a nitriding furnace forming no part of the present invention, is introduced into the furnace or shaft either after or before the heating operation. When the shaft has become sufficiently heated the source of heat, such as the gas referred to, and air, is shut off or discontinued, and the chlorin gas is introduced and caused to flow through the body or charge of briquets. The aluminum nitrid is thus converted into chlorid and the heat generated by such chemical reaction is sufficient to transform the small amount of aluminum oxid in the briquets which had not previously been charged into nitrid into aluminum chlorid, the presence of the carbon making this reaction possible. The temperature employed is unknown, but is probably about 600 degrees to 900 degrees centigrade. The chemical transformation occurs practically instantaneously, only enough chlorin gas being admitted for the reaction, no excess being used, the chemical change being controlled by the speed of introduction of such chlorin. The process thus once well initiated or established, may be practised continuously by the proper introduction of briquets at the top of the shaft and the withdrawal of the material reacted upon from the bottom of the shaft during the operation, the aluminum chlorid being sublimed and recovered in a sublimation chamber, whereas, the nitrogen seemingly goes off as a gas and is lost.

Our invention is not necessarily limited and restricted to the precise and exact features of the process set forth above, because the method may be varied more or less without departure from the substance and

essence of the invention and without the sacrifice of any of its substantial benefits and advantages, and, accordingly, the appended claims are intended to cover all 5 equivalents falling within their scope. For example, instead of using chlorin gas direct, in some cases it may be advisable to employ any suitable chemical or chemicals which at the temperature used, gives off or generates 10 the chlorin gas.

We claim:

1. The process of producing aluminum chlorid consisting in subjecting aluminum nitrid to the action of chlorin gas, substantially 15 as described.

2. The process of producing aluminum chlorid consisting in subjecting aluminum nitrid to the action of chlorin gas at a temperature from about 600 degrees to 900 degrees 20 centigrade, substantially as described.

3. The process of producing aluminum chlorid consisting in subjecting aluminum nitrid to the action of chlorin gas at a sufficient temperature to effect the conversion 25 of the nitrid into chlorid and recovering the sublimed chlorid, substantially as described.

4. The process of producing aluminum chlorid consisting in initially heating aluminum nitrid and then subjecting it to the action of chlorin gas, substantially as described.

5. The process of producing aluminum chlorid consisting in subjecting aluminum nitrid to the action of chlorin gas, initiating the reaction by outside heat, and depending upon the heat of the exothermic reaction for the continuance of the process, substantially as described.

40 6. The process of producing aluminum chlorid consisting in subjecting aluminum nitrid in briquet form to the action of chlorin gas at a sufficient temperature to effect the

conversion of the nitrid into chlorid, substantially as described.

7. The process of producing aluminum chlorid consisting in subjecting briquets containing aluminum nitrid and small portions of carbon and aluminum oxid to the action of chlorin gas, whereby both the aluminum nitrid and aluminum oxid are converted into aluminum chlorid, substantially as described.

8. The process of producing aluminum chlorid consisting in subjecting briquets 55 containing aluminum nitrid and small portions of carbon and aluminum oxid to the action of chlorin gas, whereby both the aluminum nitrid and the aluminum oxid are converted into aluminum chlorid, initiating 60 the reaction by outside heat, and depending upon the heat of the exothermic reaction for the continuance of the process, substantially as described.

9. The process of producing aluminum 65 chlorid consisting in subjecting briquets containing aluminum nitrid, about 4 to 5 per cent. of carbon, and a small amount of aluminum oxid to the action of chlorin gas at a temperature of from about 600 degrees 70 to 900 degrees centigrade, whereby the aluminum nitrid and some of the aluminum oxid are converted into aluminum chlorid, initiating the reaction by outside heat, depending upon the heat of the exothermic 75 reaction for the continuance of the process, and recovering the sublimed aluminum chlorid, substantially as described.

10. The process of producing an aluminum salt consisting in subjecting aluminum nitrid to the action of a gas of the halogen group at a sufficient temperature to effect the reaction.

EDWARD CHARLES BAUM.
DE WITT OWEN JONES.
